E. H. SHUTE.
ELECTRIC LIGHT SWITCH OPERATOR.
APPLICATION FILED MAR. 5, 1918.

1,301,183.

Patented Apr. 22, 1919.

Inventor:
Edmund H. Shute.

By Joshua C. Morris
Attorney.

UNITED STATES PATENT OFFICE.

EDMUND H. SHUTE, OF CHICAGO, ILLINOIS.

ELECTRIC-LIGHT-SWITCH OPERATOR.

1,301,183.

Specification of Letters Patent. Patented Apr. 22, 1919.

Application filed March 5, 1918. Serial No. 220,444.

To all whom it may concern:

Be it known that I, EDMUND H. SHUTE, a citizen of the United States, and a resident of the city of Chicago, county of Cook, and 5 State of Illinois, have invented certain new and useful Improvements in Electric-Light-Switch Operators, of which the following is a specification.

My invention relates to improvements in 10 electric light switch operators, and has for its object the production of a device of this character through the medium of which an electric light switch may be operated both to turn on and off the light by pulling downwardly upon a depending pull cord or handle.

A further object is the production of a device, as mentioned, which may be readily and easily applied to a conventional electric 20 light switch and which will be of durable and economical construction and efficient in use.

Other objects will appear hereinafter.

The invention consists in the combinations 25 and arrangements of parts hereinafter described and claimed.

The invention will be best understood by reference to the accompanying drawings forming a part of this specification, and in 30 which,

Figure 1 is a side elevation of a conventional electric light and switch therefor to which is applied a switch operator, embodying the invention,

Fig. 2, a side elevation of the switch operator and the adjacent portion of the light switch,

Fig. 3, a section taken on line 3—3 of Fig. 2, and

Fig. 4, a section taken on line 4—4 of Fig. 3.

The preferred form of construction as illustrated in the drawings is designed for use in connection with a conventional electric light switch connected at 5, which is provided with an oscillatory operating stem 6, the outer end of which is equipped with a flattened turn button or handle 7, whereby the light switch is ordinarily operated.

50 The device forming the subject-matter of this application comprises a cap 8 which is adapted to snugly embrace the turn button 7, pins 9 being employed, after the arrangement of the cap on the turn button, to

55 traverse the mouth of said cap and engage against the inner side or edge of the turn

button, thereby serving to securely lock the cap to the button. Embracing said cap and securely fixed thereto, is a ratchet 10, and pivotally mounted at 11 centrally upon the 60 outer end of said cap is a lever 12. Pivotally mounted at 13 upon the lever 12 is a pawl 14 adapted to coöperate with ratchet 10, as will be readily understood.

One end of lever 12 is provided with a 65 weight 15 whereby said lever will normally be held, by gravity, in a position in which the opposite end thereof, or that carrying the pawl 14, will be elevated. Connected with and depending from the last mentioned 70 end of said lever is a pull cord or other similar form of handle or pull element 16, whereby said lever may be rocked downwardly. The pawl 14 is also provided with a weight 17 at its outer end, which is adapted to normally hold said pawl in operative relation with the ratchet. With the construction set forth it will be seen that the switch stem may be intermittently rotated to turn on or off the light by successively pulling downwardly upon the member 16. Upon each successive downward pulling of the member 16, the weight 15 will operate to return the lever to initial position whereby the successive downward pulling upon the member 85 16 serves to intermittently rotate the switch stem always in the same direction.

Switch operators employing depending pull cords are in use at the present time, but some employ two cords, one for turning on the light and the other for turning it off. With applicant's construction, but one cord is necessary for performing both operations. The construction is extremely simple and may be readily and expeditiously applied to any switch employing a flattened turn button of conventional form.

While I have illustrated and described the preferred form of construction for carrying my invention into effect, this is capable of 100 variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. The combination with an electric light switch having a rotary stem and provided

with a flattened turn button; a cap embracing said turn button; a ratchet fixed to said cap; pins traversing the mouth of said cap and engaging with the inner side of said button for locking said cap to said button; and a lever pivotally mounted on said cap and having a pawl adapted for coöperation with said ratchet, substantially as described. 20

2. The combination with an electric light switch having a rotary stem and provided with a flattened turn button, of a cap embracing said turn button; pins traversing the mouth of said cap and engaging with the inner side of said button for locking said cap to said button; a ratchet fixed to said

cap; a pawl arranged for coöperation with said ratchet; an oscillatory lever carrying said pawl and adapted, through gravity, to normally assume a position in which one end thereof will be elevated; and means depending from said end of said lever for actuating the latter, substantially as described.

In testimony whereof I have signed my name to this specification in the presence of two subscribing witnesses.

EDMUND H. SHUTE.

Witnesses:

JOSHUA R. H. POTTS,
B. G. RICHARDS.
